United States Patent Office

Des. 217,181

Patented Apr. 14, 1970

217,181

LAPEL PIN

William W. Manders, Salem, N.H.
(4815 Sierra Madre Drive, San Antonio, Tex. 78233)

Filed Jan. 29, 1969, Ser. No. 15,560

Term of patent 14 years

Int. Cl. D11—01
U.S. Cl. D45—19

FIG. 1.

FIG. 3.

FIG. 2.

FIG. 1 is a front view of a lapel pin or the like showing my new design;

FIG. 2 is a right side edge view; and
FIG. 3 is a rear view thereof.

I claim:

The ornamental design for a lapel pin or the like, as shown.
